[57] CLAIM

The ornamental design for the computer keyboard and mouse storage device, as shown and described.

DESCRIPTION

FIG. 1 is a perspective view of the computer keyboard and mouse storage device of my new design;

FIG. 2 is a front elevational view thereof;

FIG. 3 is a side elevational view thereof, both sides being the same;

FIG. 4 is a top plan view thereof;

FIG. 5 is a bottom view thereof;

FIG. 6 is a back elevational view thereof; and,

FIG. 7 is a perspective view showing a keyboard and mouse in position thereof, the broken line illustration of keyboard and mouse are for illustrative purposes only and form no part of the claimed design.
